MINNIE MEYER AND ADOLF HEILBRUNN, OF NEW YORK, N. Y., ASSIGNEES TO GOLO
SLIPPER COMPANY, INC., OF NEW YORK, N. Y., A CORPORATION OF NEW YORK

DESIGN FOR A SANDAL

Application filed February 2, 1932. Serial No. 42,718. Term of patent 7 years.

To all whom it may concern:

Be it known that we, MINNIE MEYER and ADOLF HEILBRUNN, citizens of the United States, residing at New York, in the county and State of New York, have invented a new, original, and ornamental Design for Sandal, of which the following is a specification, reference being had to the accompanying drawing, forming a part thereof.

The drawing is a perspective view of a sandal showing our new design.

The dominant feature of our design resides in the ornamental effect produced by the series of wide disconnected straps interlaced diagonally to each other on the vamp of the sandal, except for the toe of the same which is left open.

We claim:

The ornamental design for a sandal substantially as shown and described.

MINNIE MEYER.
ADOLF HEILBRUNN.
